OTHER PUBLICATIONS

Design U.S. Appl. No. 29/624,451, filed Nov. 1, 2017 in the name of Newtl.

Primary Examiner — Darlington Ly(74) *Attorney, Agent, or Firm* — Carter, Deluca & Farrell LLP**(57) CLAIM**

The ornamental design for a roof of a bus, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective detailed view of a roof of a bus in accordance with the present design;

FIG. 2 is a rear perspective view thereof;

FIG. 3 is a left side elevational view thereof;

FIG. 4 is a right side elevational view thereof;

FIG. 5 is a front elevational view thereof;

FIG. 6 is a rear elevational view thereof; and,

FIG. 7 is a top plan view thereof.
